UNITED STATES PATENT OFFICE.

THOMAS H. GILHAM AND SAMUEL J. SOUDER, OF LAGRANDE, OREGON.

BEDSTEAD-FASTENING.

SPECIFICATION forming part of Letters Patent No. 673,947, dated May 14, 1901.

Application filed December 15, 1900. Serial No. 40,018. (No model.)

To all whom it may concern:

Be it known that we, THOMAS H. GILHAM and SAMUEL J. SOUDER, citizens of the United States, residing at Lagrange, in the county of Union and State of Oregon, have invented a new and useful Bedstead-Fastening, of which the following is a specification.

This invention relates to bedstead-fastenings, and has for its object to provide an improved detachable fastening for securing the side rails to the foot and head boards of an ordinary wooden bedstead without weakening the parts by letting the fastening into the rails and the end boards. It is furthermore designed to secure a snug and rigid connection between the parts of the fastening, so as to prevent looseness of the bed-frame, and finally to facilitate the engagement and disengagement of the interlocked parts, so as to permit 20 of the bedstead being readily set up and taken apart.

With these and other objects in view the present invention consists in the combination and arrangement of parts, as will be herein-after more fully described, shown in the accompanying drawings, and particularly pointed out in the appended claim, it being understood that changes in the form, proportion, size, and minor details may be made within 30 the scope of the claim without departing from the spirit or sacrificing any of the advantages of the invention.

In the drawings, Figure 1 is a perspective view of the present fastening applied to connect one end of a side rail to the adjacent end board of a bedstead. Fig. 2 is a detail sectional elevation of the fastening removed from the bedstead and showing the manner of interlocking the two members of the device. Fig. 3 is a detail perspective view of the parts separated. Fig. 4 is a transverse sectional view taken on the line 4-4 of Fig. 2.

Like characters of reference designate corresponding parts in all of the figures of the drawings.

Referring to the drawings, it will be seen that the present device comprises the end-board member 1 and the side-rail member 2, which have a detachable interlocked engagement. The end-board member is in the form of a flat plate having opposite terminal perforate ears, for the reception of fastenings 3,

whereby the member is secured flat against the inner side of the leg 4 of the adjacent end board 5, as shown in Fig. 1 of the drawings. 55 The plate is also provided with an outer intermediate extension 6, having a perforation 7 for the reception of a fastening 8 to form an additional connection to the post. Opposite the perforation 7 there is another intermediate 60 perforation 9, located adjacent to the inner edge of the plate for the reception of a wood-screw 10, as shown in Fig. 4 of the drawings. Adjacent to the inner edge of the plate and aligned longitudinally thereof are the opposite outwardly-projecting lugs 11, each of which has its upper edge provided with a wedge-shaped notch 12, which separates the upper portion of the lug from the adjacent front face of the plate, thereby forming a hook. The other member of the fastening is of substantially the same shape as the former member and has the terminal perforations and the intermediate perforate extension for the reception of fastenings 13, whereby the member is secured to the inner side of the adjacent end of the side rail 14, as shown in Fig. 1 of the drawings. Upon the outer side of the plate there is provided a longitudinally-extending and laterally-projected oblong box or casing 15, which is flush with the inner longitudinal edge of the plate and has this flush edge provided with the opposite longitudinally-aligned slots or openings 16. The inner side of this box 85 or casing is open for its entire length and has its inner ends provided with corresponding transverse shoulders 17, against which rest the opposite ends of the removable face-plate 18. (Shown in Figs. 2 and 4.) It will now be 90 apparent that the rail member of the fastening is in the form of a box or casing having opposite terminal fastening-ears and an outer intermediate fastening-ear, the inner open side of the box being normally closed by a 95 detachable face-plate, so that the interior thereof may be readily accessible to exterminate any vermin which may collect therein. The two members are interlocked by applying the casing to the lug-plate, so that the lugs are received through the respective slots 16, after which the casing is forced downwardly, so that the upper edges of the openings may be received within the respective

notches of the lugs, the engaging faces of the lugs and the inner side of the casing having corresponding bevels, as best shown in Fig. 2 of the drawings, so as to draw the members 5 together, and thereby form a snug and rigid interlocked connection therefor. The members may be readily disconnected by a reverse operation. Upon examination of Fig. 2 it will be observed that the depth of the notches 10 in the lugs is such that the engaging beveled edges thereof bind upon the adjacent inner wall portions of the casing before the top edges of the openings therein strike the bottoms of the notches, whereby increased weight 15 upon the bed tends to more firmly wedge the members together.

An additional fastening 19 is passed through the intermediate portion of the casing and the side rail of the bedstead and is provided 20 at its inner end with a nut 20, so that the head thereof is upon the outer side of the bedstead, as are all of the other fastenings, whereby the rounded heads form but slight 25 projections and are conveniently accessible for being tightened by a screw-driver.

What is claimed is—

A bedstead-fastening, consisting of oppo-

site members for attachment respectively to a corner-post and a side rail, one of the members having a flat attaching-plate provided 30 with perforations for the reception of fastenings, and a plurality of laterally-projected lugs or projections provided in corresponding edges with wedge-shaped notches, of which the plate forms the inner edges, the other member consisting of a box having outwardly-directed perforate marginal attaching-ears 35 flush with the inner side thereof, the outer edge of the box being provided with slots or openings corresponding to and for the reception of the respective lugs or projections of the former member, and corresponding end edges of the slots being beveled upon their inner sides to correspond to and snugly fit 40 against the outer beveled or inclined edges of 45 the notches of the respective projections.

In testimony that we claim the foregoing as our own we have hereto affixed our signatures in the presence of two witnesses.

THOMAS H. GILHAM.
SAMUEL J. SOUDER.
